UNITED STATES PATENT OFFICE.

EZRA L. WHISLER, OF CENTRALIA, WASHINGTON.

CLOTHES-WASHING APPARATUS.

1,172,651.

Specification of Letters Patent. Patented Feb. 22, 1916.

Application filed May 17, 1915. Serial No. 28,658.

To all whom it may concern:

Be it known that I, EZRA L. WHISLER, a citizen of the United States, residing at Centralia, in the county of Lewis and State 5 of Washington, have invented certain new and useful Improvements in Clothes-Washing Apparatus, of which the following is a specification.

This invention contemplates an improved 10 clothes washing apparatus and has as its primary object to provide a device of this character adapted to adjustably support a clothes pounder or other suitable working element in such manner that the said pounder may 15 be shifted from one washing receptacle to another to be used in each thereof.

The invention has as a further object in 20 this connection to provide a swingingly mounted carriage for the clothes pounder or working element, and wherein the said carriage will be adapted to operatively support the clothes pounder adjacent the receptacle and independently thereof in such 25 position that the pounder may be easily actuated to wash the clothes within the receptacle.

A still further object of the invention is 30 to provide an improved mounting for the clothes pounder and to also provide an improved actuating mechanism therefor of such character that the pounder may be easily and effectively operated with a minimum expenditure of labor.

Other and incidental objects will appear 35 as the description proceeds and in the drawings wherein I have illustrated the preferred embodiment of my invention and wherein similar reference characters designate corresponding parts throughout the several 40 views. Figure 1 is a perspective view of my improved apparatus showing the device applied to a conventional type of support. Fig. 2 is a top plan view of the device, this view showing in dotted lines, the manner 45 in which the clothes pounder carriage may be adjusted. Fig. 3 is a fragmentary elevation showing the guide for the operating lever of the device. Fig. 4 is a fragmentary section view of the pounder, and Fig. 5 is 50 a fragmentary perspective view showing a slightly modified form of attaching plate.

In the preferred embodiment of my invention as illustrated in the drawings, I employ an attaching plate 10. Extending 55 laterally from the plate and preferably having screw threaded engagement therewith,

is a tubular extension 11. Mounted upon the extension 11 is an elbow 12 in which is screw threaded a post 12'. Swingingly mounted upon the post 12' is a T-coupling 60 to which is connected an arm 13. Screw threaded upon the arm 13 is another elbow 14 which carries an upstanding terminal arm 15.

Swingingly mounted upon the arm 15 is 65 a sleeve 16 in the nature of a T-coupling and which supports an arm 17, the arm 17 preferably having screw threaded engagement with the said coupling. Screw threaded upon the outer terminal of the arm 17 is an 70 elbow 18 which carries a terminal headed upstanding arm 19.

From the preceding description it will be seen that the arms 17 and 19 may be swung in the arc of a circle upon the sleeve 16, with 75 the arm 15 as the center.

Freely mounted upon the arm 19 adjacent opposite extremities thereof, are spaced sleeves 20 and 21, each of which is also in the nature of a T-coupling. It will be observed that the sleeve 20 abuts the elbow 18, 80 while the sleeve 21 abuts the head of the arm 19. Interposed between the sleeves 20 and 21 and mounted freely upon the arm 19 are a plurality of spacing sleeves 22 and 85 23, said sleeves being preferably three in number.

Screw threaded into the couplings 20 and 21 are substantially parallel laterally extending arms 24, to the outer terminals of 90 which are preferably detachably connected sleeves 25 also in the nature of T-couplings. Connecting the sleeves 25 is a preferably flat bar 26. As best shown in Fig. 3 of the drawings, the bar 26 is greater in length 95 than the distance between the sleeves 25 and projects laterally beyond the sleeves and beyond the arms 24, the said bar being arranged parallel with the said sleeves 25 and being secured thereto in lateral spaced relation by connecting webs 27.

Mounted upon the bar 26 is a guide 28. The guide 28 is preferably formed from a single length of wire, one terminal of which is secured to the bar 26 adjacent the lower 105 extremity thereof and projects laterally from the bar as best shown in Figs. 1 and 2 of the drawings. The intermediate portion of the wire is then bent to extend substantially parallel with the bar 26 in spaced 110 relation thereto to a point beyond the upper end of the bar. The wire is then again bent

laterally as shown at 29 and is thence continued to form a retaining loop 30 extending substantially parallel to the inner face of the adjacent upper extremity of the bar 5 and in spaced relation thereto, the terminal of the wire being directed laterally and secured to the adjacent upper terminal of the bar as shown at 31.

Slidably mounted for vertical movement 10 through the sleeves 25 is a preferably tubular rod 32 which, at its upper extremity, is provided with a head 33 having screw threaded engagement therewith. Extending laterally from the head 33 is a headed arm 15 or lug 34.

As best shown in Fig. 1 of the drawings, the sleeve 23 of the arm 19 is provided with a laterally projecting pivot pin or arm 35 and detachably and pivotally mounted upon the 20 said arm is a preferably flat operating lever 36 which extends freely between the guide 28 and the bar 26 and provides a handle for the device. Pivotally connected to the lever 36 is an arm 37, the outer terminal 25 of which is freely connected to the arm 34 of the plunger rod 32. As shown in dotted lines in Fig. 1 of the drawings, the arm 37 may be reversed in its position relative to the lever 36, this arrangement providing for 30 a variation in the throw of the plunger rod.

From the preceding description, it will be readily seen that the sleeves 20 and 21, the arms 24, and the sleeves 25, provide a carriage for the plunger rod 32 adapted for 35 movement in an arcuate path about the arm 18 as an axis. These elements just previously enumerated also provide a carriage for the operating lever 36 and associated mechanism which is adapted to swing therewith, 40 as the carriage is shifted upon its pivot, while the said carriage and its associated elements may be bodily swung in an arcuate path upon the arm 17 about the arm or shaft 15 as an axis and may also be swung upon 45 the arm 13 about the post 12' as an axis.

Connected to the inner terminal of the rod 32 is a pounder indicated as a whole in Fig. 1 of the drawings by the numeral 38 and as will be clear from the preceding description, 50 said pounder may be readily reciprocated through the medium of the operating lever 36 and the arm 37. In use, the device may be suitably attached to the upright of a conventional form of wringer bench 39 shown 55 in Fig. 1 of the drawings, in the manner therein illustrated, the uprights of said bench supporting a wringer 40. As is usual, a receptacle is placed upon each side of the wringer so that clothes from one receptacle 60 may be passed through the wringer and caught within the other receptacle. When so mounted, the carriage supporting the pounder may be swung upon the shaft 19 to dispose the pounder over first one receptacle 65 and then the other so that by moving the

operating lever 36 up and down, the pounder may be actuated to thoroughly clean the clothes within each of the receptacles. In the event the adjustment of the carriage obtainable around the shaft 19 is not sufficient 70 to reach either of the receptacles, the entire carriage and associated mechanism may be further adjusted upon the shaft 15 or upon the post 12' in the manner previously described. Thus, the pounder may be moved 75 or shifted to reach quite a number of receptacles when arranged in a row upon the bench 39.

Particular attention is now directed to Fig. 3 of the drawings wherein I have illustrated the manner in which the operating lever 36 is moved to lock the plunger in inoperative position. It will be noted that the retaining loop 30 is adapted to receive the said lever to rest upon the laterally directed 80 terminal 31 thereof with the lever disposed in the rear of the adjacent upper terminal of the bar 26. Consequently, the upper terminal of the bar provides a retaining lug for the lever adapted to hold the lever in inoperative position until at such time it is manually operated to move the lever upwardly to clear the adjacent upper end of the bar. In use, when the lever 36 is reciprocated to actuate the plunger rod 32, the 85 said lever will move freely between the guide 90 and the bar 26.

In Fig. 4 of the drawings, I have illustrated the preferred form of pounder employed in connection with my improved apparatus although as will be readily understood, any other suitable type of pounder may be used in connection therewith. As illustrated in this figure of the drawings, the pounder preferably includes a substantially 100 frusto-conical shell 41. Connected to the smaller end of the shell is a socket 42 which detachably receives the adjacent extremity of the plunger rod 32.

Formed in the wall of the shell 41 adjacent the smaller end thereof is an annular series of spaced openings 43 and secured to the shell and overhanging said series of openings is an annular flange 44, the lower free terminal of said flange being arranged 115 in spaced relation to the wall of the shell.

Arranged within the shell 41 adjacent the smaller end thereof is a partition 45 which, adjacent its periphery, is provided with an annular series of spaced openings 46. Mounted upon the partition 45 and arranged axially within the shell 41 in spaced relation thereto is a substantially frusto-conical spreader 47 having its smaller end presented 120 toward the smaller end of the shell 41. The inner end of the spreader 47 is open, while, at the lower end thereof, the wall of the spreader is turned to provide a bead 48.

It will thus be seen that I provide a very simple and efficient form of pounder which 130

may be readily formed from suitable sheet metal and which will, in use, prove entirely effective.

In Fig. 5 of the drawings, I have shown a slightly modified form of attaching plate 49 which is provided with an upstanding headed post 50 to which is swingingly connected the arm 13, as in the preferred form of the invention. The attaching plate of this modification discloses an arrangement whereby my improved device may be connected to a horizontal support, while the attaching plate of the preferred form is more particularly designed for use in connection with a vertical support as illustrated in the drawings.

Having thus described my invention, what I claim and desire to secure by Letters Patent is:—

1. A device of the character described including a swingingly supported post a shaft swingingly connected to the post, a carriage freely connected with the shaft, a plunger having slideable connection with said carriage, and an operating lever freely secured to the shaft and having operative connection with said plunger.

2. A device of the character described including a shaft, means operatively supporting the shaft, a carriage including sleeves freely embracing the shaft, a sleeve upon the shaft and operatively supporting said first mentioned sleeves in spaced relation, arms extending from said first mentioned sleeves, and sleeves carried by said arms, a plunger freely mounted in said last mentioned sleeves, and an operating lever freely secured to said second mentioned sleeve and having operative connection with said plunger.

3. A device of the character described including a shaft, means swingingly supporting the shaft, a carriage freely connected to the shaft, a plunger mounted to reciprocate upon the carriage, a bar carried by the carriage, a guide supported by said bar, and an operating lever freely secured to the shaft and having operative connection with said plunger, said lever extending freely between the said guide and the bar.

4. A device of the character described including a shaft, means operatively supporting the shaft, a carriage swingingly connected to the shaft, a plunger mounted to reciprocate upon the carriage, a bar carried by the carriage, a guide supported by said bar, an operating lever freely and pivotally connected with said shaft, the lever extending freely between the said bar and the guide, and an arm having pivotal connection with the lever and with said plunger whereby actuation of the bar will reciprocate the plunger, said arm being reversible in its relation to the plunger to adjust the throw of said plunger.

5. A device of the character described including a shaft, means operatively supporting the shaft, a carriage swingingly connected with the shaft, a plunger mounted for reciprocation upon the carriage, a bar carried by the carriage, a guide supported by said bar and coöperating therewith, to provide a retaining loop, and a lever freely secured to said shaft and having operative connection with the plunger, the said lever extending freely between the said bar and guide and being adapted for engagement in said loop for holding the plunger in elevated position.

6. A device of the character described including a shaft, means swingingly supporting the shaft, a carriage swingingly connected to the shaft, a plunger mounted for reciprocation upon the carriage, a lever shiftable with the carriage and operatively connected with the plunger, and a guide for the lever carried by the carriage and adapted to be engaged by the lever for maintaining the plunger in elevated position.

7. A device of the character described including a shaft, means operatively supporting the shaft, a carriage swingingly connected to the shaft, a bar carried by said carriage, a guide extending in spaced relation to the bar and embracing the bar at one end thereof, the adjacent end of the bar providing a stop lug coöperating with the guide to form a retaining loop, a plunger mounted upon the carriage, and an operating lever operatively secured at one extremity to said shaft and extending freely between the guide and said bar, the lever being adapted for movement to a position supported by said retaining loop and engaged by said stop lug for maintaining the plunger elevated.

8. A device of the character described including a rigid supporting post, a second post swingingly connected to said first mentioned post, a shaft swingingly connected to said second mentioned post, a carriage mounted to swing about the shaft, a plunger mounted to reciprocate upon the carriage, and an operating lever for the plunger.

9. A device of the character described including a swingingly supported carriage, a plunger mounted to reciprocate upon the carriage, an operating lever movable about the axis of the carriage, and a link pivotally connecting the lever with the plunger, the said link being adjustable upon the lever to vary the throw of the plunger.

10. A device of the character described including a carriage, a plunger mounted to reciprocate upon the carriage, a guide bar carried by the carriage, and an operating lever arranged to coöperate with said bar and having operative connection with the plunger, the said lever being shiftable to position between the bar and plunger for supporting the plunger in elevated position.

11. A device of the character described in-

cluding a carriage, a plunger mounted to reciprocate upon the carriage, a guide bar carried by the carriage, a guide associated with the bar and looped over one extremity thereof, and an operating lever mounted for movement between the guide and said bar and having operative connection with the plunger, said lever being shiftable to engage in said loop of the guide for supporting the plunger in elevated position.

12. A device of the character described including a carriage, a plunger mounted to re-

ciprocate upon the carriage, an operating lever for the plunger, a bar carried by the carriage, and a guide for the lever carried by said bar and formed to provide a stop adapted to be engaged by said lever for supporting the plunger in elevated position.

In testimony whereof I affix my signature in presence of two witnesses.
